(57) **CLAIM**

The ornamental design for an infrared electronic thermometer, as shown and described.

DESCRIPTION

FIG. 1 is a top, front and right side perspective view of an infrared electronic thermometer showing our new design; FIG. 2 is a bottom, rear and right side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

The broken lines in the drawings illustrate portions of the infrared electronic thermometer which form no part of the claimed design.

The oblique shade lines in FIG. 2 and FIG. 4 represent reflective surfaces.
